SEMITRANSPARENT REFLECTING FILTER
FOR CATHODE-RAY TUBES

Joseph Kaplan, Philadelphia, Pa., Michael L. Kaplan, New Rochelle, N. Y., and Samuel Williams, Philadelphia, Pa., assignors to Sightmaster Corp., New York, N. Y., a corporation of New York

Application March 9, 1948, Serial No. 13,864

3 Claims. (CL 178—7.5)

1

This invention relates to television receivers employing a cathode ray tube having a fluorescent screen at the large end of the tube upon which the received pictures are formed by the scanning cathode ray beam.

It is an object of this invention to provide a television receiver employing such cathode ray tube, the fluorescent screen end of which is protected by safety glass which gives a pleasing tinted cast to the picture when the television receiver is in use, and which, when the receiver is not in use, imparts an attractive ornamental appearance and serves a useful function.

Another object is to provide such television receiver in which the combination of cathode ray tube and protective safety glass are separately mounted from the control panel for the television receiver permitting unusually pleasing decorative disposition of the screen, which, when the television receiver is not in use, does not give the appearance of a television screen.

Other objects and advantages of this invention will be apparent from the following detailed description thereof.

In accordance with this invention a cathode ray tube having a fluorescent screen at the large end thereof has mounted immediately in front of the tube in a plane at right angles to the longitudinal axis of the tube and completely covering the fluorescent screen end of the tube a pane of safety glass, the side of which closest to the fluorescent screen is provided with a semi-transparent reflecting surface. Such reflecting surface, we have found, imparts a very pleasing tinted cast to the picture when the receiver is in use, the tint depending upon the nature of the semi-transparent reflecting surface. It further improves the clarity of the picture. When the television receiver is not in use the safety glass having the semi-transparent reflecting surface functions as a mirror. Hence, when this invention is embodied in a cabinet type television receiver an unusually attractive appearance is imparted thereto, the face of the cabinet functioning as a mirror. The combination of the cathode ray tube and safety glass having a semi-transparent reflecting surface may be disposed in a wall or other surface so that only the safety glass is exposed to view, the control panel being separately mounted where it is readily accessible for operation, resulting in unusually pleasing decorative effects.

In the accompanying drawing forming a part of this specification and showing, for purposes of exemplification, preferred forms of this in-

2

vention without limiting the claimed invention to such illustrative instances.

Figure 1 is a perspective view of a cabinet type television receiver embodying this invention, the cathode ray tube within the cabinet being shown in dotted lines;

Figure 2 represents a cathode ray tube and protective safety glass embodying this invention mounted separately from the control panel for the television receiver; and

Figure 3 is a vertical section through the protective safety glass shown on a greatly enlarged scale as compared with the scale of the other figures.

In the drawing 10 indicates a television receiving cabinet of any desired type having on its face 11 usual control knobs 12 and a frame 13, in which is suitably mounted a pane of safety glass 14 hereinafter more fully described. A cathode ray tube 15 having a fluorescent screen 16 at the large end thereof is mounted in conventional manner within the cabinet 10. The fluorescent screen 16 is disposed just behind the safety glass 14, the safety glass being so dimensioned that it completely covers and exposes to view the entire area of fluorescent screen 16. It is disposed in a plane at right angles to the longitudinal axis of the tube 15.

The safety glass 14 desirably is of laminated construction and consists of two layers 17 and 18 of plate glass inseparably bonded by an intervening layer 19 of transparent plastic material, such as cellulose nitrate, cellulose acetate, or a polyvinyl resin, preferably polyvinyl butyral. A semi-transparent reflecting surface 20 is formed on the side of the safety glass 14 positioned closest to the fluorescent screen 16. This semi-transparent reflecting surface may be produced, for example, by depositing silver nitrate on side 21 of layer 18, which may be of grained glass, and reducing the silver nitrate to form a semi-transparent silver film. The semi-transparent reflecting surface may, if desired, be formed by depositing a reflecting metal on side 21 of layer 18 by the known cathode sputtering method or by evaporating the metal and causing the vapor to contact the glass or by electrodeposition. While it is preferred to deposit silver to form a silver reflecting surface, other metals, such as gold, platinum, chromium, or copper, may be deposited on side 21 of layer 18 to form the desired semi-transparent reflecting surface. The amount of metal thus deposited on side 21 of layer 18 should be such as to impart a semi-transparent reflecting surface, i. e., permit light rays to penetrate so

that the picture is visible through the safety glass laminate 14, and, when the receiver is not in use, produce a mirror. A layer of metal of a thickness of from 1×10^{-6} to 100×10^{-6} mm., preferably from 5×10^{-6} to 30×10^{-6} mm. is satisfactory.

The combination of cathode ray tube having the fluorescent screen and safety glass having a semi-transparent reflecting surface disposed in a plane at right angles to the longitudinal axis of the cathode ray tube hereinabove described has been found to impart an unusually attractive pleasing tinted cast to the picture and further to improve the clarity of the picture. The tint will depend upon the nature of the metal deposited on side 21 of layer 18. Thus, in the case of a silver metal surface on a grained glass a pleasing blue tint is imparted to the picture; by incorporating dye stuffs in the metal deposited on layer 18, or by the use of other metals, a picture of any desired tinted cast may be produced.

The combination of the cathode ray tube 15 and the protective safety glass 14 disposed with the safety glass in a plane at right angles to the longitudinal axis of tube 15 may, if desired, be mounted separately from the control panel 22 therefor. For example, the cathode ray tube 15 and the safety glass 14 may be mounted within a wall 23 of a room so that the face of safety glass 14 is flush with the surface of the wall, as shown in Figure 2, and the cathode ray tube 15 is disposed with the fluorescent screen 16 in back of the safety glass 14, as shown in Figure 3, the cathode ray tube being connected by a suitable lead 14 with the control panel 22. This panel has suitable control knobs 25, 26 controlling the operation of the television receiver. In this way the safety glass 14 may be disposed so as to impart an unusually pleasing decorative appearance to the wall or other surface with which it is associated. For example, it may resemble a mirror on or set within a wall when the television receiver is not in use, and thus camouflage the television screen when not in use.

In the embodiment of Figure 2, a magnifier 27 desirably in the form of a magnifying lens is interposed between the fluorescent screen 16 and the safety glass 14. Such magnifier may be omitted from the construction of Figure 2 or employed in the cabinet type of receiver shown in Figure 1 suitably mounted between screen 16 and safety glass 14. Desirably magnifier 27 is a magnifying lens of an area somewhat greater than that of screen 16 and is spaced from this screen a distance such that the person viewing the screen sees a magnified image of the picture. The safety glass 14 conceals the magnifying lens yet permits the magnified image to be viewed and imparts a pleasing tint thereto.

It will be noted this invention provides a television receiver employing a cathode ray tube having a fluorescent screen which is protected by a pane of safety glass imparting a pleasing tinted cast to the picture when the television receiver is in use, and which, when the television receiver is not in use, has an unusually attractive ornamental appearance and serves as a mirror.

Since different embodiments of this invention could be made without departing from the scope thereof, it is intended that all matter in the above description or shown in the accompanying drawing shall be interpreted as illustrative and not in a limiting sense. For example, while a safety glass laminate has been shown and de-

scribed above, it will be understood other visually transparent protective surfaces having a semi-transparent reflecting surface on the side closest to the cathode ray tube may be used in lieu of the safety glass. Further while in Figure 3 the semi-transparent reflecting surface 21 is shown disposed on the back of layer 18, it may be positioned on the side of this layer in contact with plastic layer 19 so that when the laminate is formed the semi-transparent reflecting surface is hermetically sealed between layers 18 and 19 and thus protected against deleterious influences arising from exposure to the atmosphere. In the case of a silver reflecting surface, for example, which tends to tarnish and decompose on exposure to the atmosphere, it is preferred to have the silver layer on the side of glass 18 immediately adjacent the plastic layer 19 so that the surface of the silver layer is hermetically sealed.

What is claimed is:

1. In a television receiver, in combination, a cathode ray tube having a fluorescent screen at the large end thereof, a visually transparent protective member, means on said member to cause said member to act as a mirror when said cathode ray tube is de-energized, said means comprising a semi-transparent metallic reflecting surface on the back of said member, and means mounting said member so that it is spaced from, close to, and in front of said cathode ray tube in a plane at right angles to the longitudinal axis of said tube.

2. A television receiver, as defined in claim 1, in which the visually transparent protective member consists of a transparent laminate comprising an intermediate layer of transparent plastic material, and said means comprising a semi-transparent metallic reflecting surface is disposed contiguous to said intermediate layer of transparent plastic material.

3. A television receiver, as defined in claim 1, in which said visually transparent protective member consists of a pane of safety glass comprising two sheets of glass inseparably bonded with an intermediate layer of transparent plastic material, and said means comprising a semi-transparent metallic reflecting surface is disposed on one side of one of said sheets of glass contiguous to said layer of transparent plastic material, thus hermetically sealing the semi-transparent metallic reflecting surface between the two sheets of glass.
